T. W. BEVAN,
SURGICAL BEDSTEAD,
APPLICATION FILED JULY 3, 1916.

1,242,315.

Patented Oct. 9, 1917.

Inventor:
Tom Webb Bevan
By *Tom Webb Bevan*

UNITED STATES PATENT OFFICE.

TOM WEBB BEVAN, OF NANTYGLO, WALES.

SURGICAL BEDSTEAD.

1,242,315.

Specification of Letters Patent.

Patented Oct. 9, 1917.

Application filed July 3, 1916. Serial No. 107,424.

To all whom it may concern:

Be it known that I, TOM WEBB BEVAN, subject of the King of Great Britain, residing at Nantyglo, Monmouthshire, Wales, 5 have invented certain new and useful Improvements in Surgical Bedsteads, of which the following is a specification.

This invention relates to improvements in the construction of surgical bedsteads, of 10 that kind wherein the surface for the support of the patient can be placed at an inclination to the horizontal plane, and which bedsteads are fitted with means for applying tension to the limbs of the patient.

15 The object of the present invention is to provide a convenient and simple construction of such a bedstead which can be employed in the ordinary position of a bedstead and then present the usual appearance there- 20 of, while on the other hand by mechanical adjustment the bedstead can be placed at any desired inclination and can be arranged to permit of extension devices being applied thereto.

25 According to this invention I make the bedstead to conform to the ordinary or usual design, but with the legs at the foot thereof extensible in length, so that when extended the ordinary supporting surface of the bed- 30 stead will incline downwardly from the foot toward the head, and when thus inclined the bedstead can be readily moved for cleaning purposes or the like without altering its adjustment. Such a bedstead is provided with 35 a detachable member over which the usual flexible weight-carrying connection passes which is employed in cases where extension is required, the said member being adjusted in such relation to the foot frame of the

40 bedstead that the weight hangs clear of the framework when the bedstead is placed at an inclination to the horizontal, and the said member is so constructed that it can be entirely removed when not required for use 45 and leave the foot frame of the bedstead un- encumbered.

Beyond this I preferably form the side frames of the bedstead substantially square in section or at all events of a section presenting two parallel vertical sides and a horizontal top portion in order that clamps may be more readily fixed to such frames for enabling pulls in different directions to be obtained.

55 The invention will be described with

reference to the accompanying drawings, whereon—

Figure 1 shows a bedstead according to this invention with the bedstead adjusted to an inclined position, and the member over which the usual flexible weight-carrying connection passes placed *in situ*. Fig. 2 is an elevation of a portion of the framework at the foot end of the bedstead, and Fig. 3 is a transverse section of one of the side rails 65 of the bedstead.

Referring to Fig. 1 of the drawings, the detachable member over which the flexible weight-carrying connection is to pass consists of two arms 1, 2, the ends of which are 70 connected together by a rod, which rod carries, in the instance illustrated, a revoluble tube or roller 3. The arms 1, 2 of this member or extension frame are adapted to be passed freely through sockets or loops 4 75 (Figs. 1 and 2) fixed on the vertical members 5, 6 of the foot frame of the bedstead, the said arms 1, 2 extending when so placed upon each exterior side of the side frames 7, 8; the arms may be conveniently formed 80 with holes as shown, while the side frames 7, 8 are similarly formed with a series of holes, and pins, such as 9, may be passed through one of the holes in each of the arms 1, 2 and through corresponding holes 85 in the side frames 7, 8, so that the roller 3 may be adjusted to any required position extending beyond the foot frame of the bedstead, and the flexible connections of the extension apparatus can then be passed over 90 the roller 3 and the weight carried by such flexible connections will hang clear of the bedstead.

Obviously instead of the roller 3 a loose pulley may be freely mounted on the rod 95 extending between the arms 1, 2, which pulley can be adjusted lengthwise upon the rod to any required position, but I have found the roller shown to answer the purpose well.

100 It will be readily understood by manufacturers acquainted with the art, that numerous modifications of construction may be easily devised by which the roller 3 or a rod or the like carrying a pulley can be 105 detachably attached to the frame of the bedstead, while at the same time being capable of adjustment in position, but the construction I have illustrated is sufficient to enable a proper understanding of the 110

nature of my said invention and in what manner the same is to be performed.

In the construction illustrated, by suitable adjustment of the arms 1, 2 the roller 3 can be adjusted so as to project more or less beyond the foot frame of the bedstead and can be varied to some extent in height, while at the same time when this extension frame is not required it can be entirely removed and leave the foot frame of the bedstead unencumbered.

I preferably construct the frame of the bed, such as the side frames 7, 8, either square in section or of channel section in which the flanges extend downwardly as for instance is illustrated at Fig. 3, so that clamps can be more easily fixed to such frames for enabling pulls in different directions to be obtained in extension cases.

20 The legs of the head frame of the bedstead are of ordinary construction and are not extensible, while the legs of the foot frame of the bedstead are made extensible, and in the drawing at Fig. 1 the casters 10 carry stems 11 which are capable of sliding telescopically within the tubular legs 12 of the foot frame of the bedstead, and said telescopic legs are held at the required extension by any suitable means, but preferably by a simple means such as shown in the drawings where a series of holes are formed through the stems 11, and holes through the tubular legs 12, so that the pins 13 can be passed through the said holes as indicated in the drawing to retain the legs of the foot end of the bedstead at the length to which they have been adjusted.

Such a bedstead it will now be understood can be used in the ordinary position of a bedstead and present the usual appearance thereof, by simply reducing the length of the legs 12 at the foot end to the same length as those at the head end and by removing the extension member comprising the arms 1, 2 with the rod 3; when such a bedstead is required to be employed in extension cases it will be obvious that it can be arranged at any desired inclination, and the detachable member over which the flexible weight-carrying connections are to pass can be easily placed in any required position. With the foot end thus raised to the proper extent the weight of the body of the

patient acts against the pull of the usual weight. 55

What I claim as my invention and desire to secure by Letters Patent is:—

1. A surgical bedstead having in combination, means for elevating one end of said bed and a member comprising two parallel arms, one end of one arm and the corresponding end of the other arm being connected by a transversely extending bolt, a freely revoluble roller mounted on said bolt, a loop fixed externally on the outer side of each of the vertical members of the foot frame of the bedstead through which loops said arms are passed, said arms having a series of holes, and the longitudinal side frames of said bedstead also having a series of holes, pins to pass through the holes in said arms and through the said holes in the said side frames of said bedstead to secure said arms in an angular position with said roller projecting beyond the foot end of said bedstead.

2. In surgical bedsteads; the combination of two non-extensible legs at the head end of said bedstead, two extensible legs at the foot end of said bedstead, and a member comprising two parallel arms, one end of one arm and the corresponding end of the other arm being connected by a transversely extending bolt, a freely revoluble roller mounted on said bolt, a loop fixed externally on the outer side of each of the vertical members of the foot frame of the bedstead through which loops said arms are passed, longitudinal side frames of a section presenting two parallel vertical sides and a horizontal top portion, said arms having a series of holes, and the longitudinal side frames of said bedstead also having a series of holes, pins to pass through the holes in said arms and through the said holes in the said side frames of said bedstead to secure said arms in an angular position with said roller projecting beyond the foot end of said bedstead.

In witness whereof I have hereunto set 100 my hand in the presence of three witnesses.

TOM WEBB BEVAN.
